END WALL FOR RAILWAY CARS

Albert G. Dean, Narberth, Pa., assignor to The Budd Company, Philadelphia, Pa., a corporation of Pennsylvania

Application October 24, 1947, Serial No. 782,005

9 Claims. (Cl. 105—402)

1

The invention relates to a railway car and especially to an end wall construction for such a car. Still more specifically, the invention relates to the construction of the collision posts connected with the end wall and to an upper brace or structure interconnecting such posts.

The invention is related to applicant's pending application Serial No. 619,824, filed October 2, 1945, for "Railway car end."

An object of the invention is to provide an end wall construction which is simple and strong and which, in addition to its regular function of stress transmission, fulfills other functions which ordinarily are either absent or fulfilled by additional structural members.

Another object of the invention is to provide a construction in which water collecting on the roof is efficiently discharged by simple means so that it is kept away from most of the equipment arranged on the outside of the car ends and so that persons standing on a station platform next to the train will not be splashed with water, as is often the case with previous constructions.

A further object of the invention is to provide a combination of means associated with the collision posts which permit the attachment of lifting means for the car and which efficiently transmit the weight of the car over large areas of the adjacent body structure.

With the aforesaid main objects in view, the invention consists in the construction and arrangement of different parts of a railway car, as illustrated in the attached drawing and described hereinafter. However, it should be understood that the drawing merely illustrates an embodiment of the invention and that the invention is not restricted to every illustrated detail.

In the drawing:

Figure 1 is an elevation of the end wall of a railway car;

Figure 2 is a fragmentary section through the upper central portion of the end wall and the adjoining margin of the roof along line 2—2 of Figure 1;

Figure 3 is an underside view of one end of the cross brace interconnecting the collision posts and a section through one of said posts and the adjoining part of the end wall, the view and section being taken along line 3—3 of Figure 1;

Figure 4 is a fragmentary section along line 4—4 of Figures 1 and 3 showing the meeting point between cross brace and one collision post;

Figure 5 is a fragmentary transverse section along line 5—5 of Figure 1 through the upper part of the end wall and the adjoining roof show-

2

ing the upper part of one of the collision posts in side elevation; and

Figure 6 is a fragmentary section along line 6—6 of Figure 5.

5 In the illustrated construction, an end wall panel 10 has its margins secured to a bottom end sill 11 of the underframe, the end posts 12 of the side walls, and the end margin of the roof 13, which latter has transversely spaced hat section 14 and longitudinally corrugated sheeting 15. The end wall panel surrounds at top and sides a central passage opening 16, which opening is flanked at the sides by collision posts 17 and reinforced at the top by a cross member 18. The end wall panel may be further reinforced by braces on its inside and/or outside, as is quite customary.

10 The collision posts 17, presenting hollow-section reinforcing structures, extend over the full height of the end wall and over most of the height of the bottom end sill. The posts 17 have hat cross section, each comprising an outer wall 19, an inner side wall 20, an end wall 21 and lateral flanges 22, the latter serving for the overlapping structural connection with the end wall panel 10 and the bottom end sill 11. The posts have their lower ends open at 23 (see fragmentary section at lower end of right post in Figure 1).

15 20 25 30 35 40 45 The cross member 18 interconnecting the collision posts 17 above the passage opening 16 is arranged a short distance below the upper margin of the end wall. This brace presents a closed box section formed by the adjoining part of the end wall panel 10, an upper channel section 24, inverted channel section 25 and a vertical web 26. The side walls of the channel sections 24 and 25 are overlappingly secured, as by spot welding, to the panel 10 and the web 26. In end view (Figure 1), the cross brace has triangular form so that the bottom of the channel section 24 slopes from the middle toward the collision posts.

45 Located in the interior of the cross brace 18 and secured to the brace is a sleeve 27 for a coil spring. This spring is part of the diaphragm construction for enclosing the passage between adjacent cars. Neither the spring nor the diaphragm is illustrated.

50 55 The ends of the cross brace channel 24 are structurally and water-tightly connected with the inner walls 20 of the collision posts. The walls 20 are provided with openings 28 which extend from the adjoining end of the bottom wall of channel member 24 a short distance upwardly.

The sloping bottom wall of channel section 24 directs water entering this channel toward the collision posts 17 where it enters the interior of the posts through the openings 28 and is discharged through the bottom openings 23. In other words, the cross brace presents a trough structure and the collision posts serve as drain pipes for water collected by the cross brace so that such water cannot spill over persons standing close to the car and will not run over the full height of the side walls damaging or making inoperative, especially in freezing weather, the equipment supported by the end wall.

The roof sheeting 15 terminates at the end wall panel 10 and is secured to a marginal reinforcement 29 thereof. The purlines 14, however, extend in part beyond the end wall panel 10. These purlines 14 are hat sectional having a top wall 30, side walls 31 and flanges 32. The flanges 32 end at the end wall panel 10 and the reinforcement 29 but are cut off from the portions of the walls 30, 31 projecting therebeyond. The purlines 14 are arranged in vertical planes with the respective collision posts 17 so that the projecting parts of the purline walls 30, 31 close the open ends of the posts to which they are welded.

The side walls 19, 20 of the posts have their upper ends cut out at 33 and the lower portions of the purline walls 31 have registering cut-outs in the region of overlap with the posts so that large openings are provided. Arranged in the interior of the overlapping ends of each post and purline is an annular member 34 which preferably consists of a casting or forging. This reinforcement 34 may project inwardly beyond the margins of the cut-out 33 in the posts and the purlines to which it is secured by arc or gas welding or other appropriate means.

The upper openings 33 in the posts, together with the annular reinforcing members 34, present ears permitting the convenient attachment of a hoist when the vehicle body is to be lifted from one place to another during its manufacture, when it is to be lifted later on and again put on its supporting trucks, or when it has to be lifted in the case of a derailment.

Water collecting on the middle portion of the roof will be confined by the purlines and forced to flow over the end of the central roof sheeting onto the cross brace 18 whence it is discharged as described hereinbefore.

On account of the arrangement of the cross brace lower than the lifting ears, the latter do not participate in the discharge of the water while the arrangement of the ears in combination with the collision posts and the purlines effectively transmits the weight over large areas of end wall and roof as well as into the under-frame.

The illustrated structure consists mostly of sheet metal parts and preferably of stainless steel or other non-corrosive metal so that the question of corrosion of the interior of the posts need not be considered.

Connection between the parts is made preferably by overlapped spot welding.

Protection is sought for the invention as covered by the spirit and the language of the attached claims.

What is claimed is:

1. In a railway car, an end wall, hollow-section reinforcing structures extending vertically across said wall on both sides of the middle thereof, a trough structure extending between said rein-

forcing structures in the upper region of and adjoining said wall, an opening in at least one of the reinforcing structures communicating with said trough structure, said last-mentioned reinforcing structure having another opening at its lower end thereby serving as drain pipe for water collected by said trough structure.

2. In a railway car, an end wall, a hollow-section elongated reinforcement secured to and extending vertically across said wall, a trough structure extending from and transversely to said reinforcement in the upper region of said end wall, an opening in one side of said reinforcement communicating with said trough structure, said reinforcement having another opening at its lower end so that it serves as drain pipe for water collected by said trough structure.

3. In a railway car, an end wall having its lateral and top margins connected with the car side walls and roof, a pair of collision posts structurally connected to and flanking a passage opening in said wall, a transverse brace above said opening bridging the space between said posts and structurally connected with them and with said wall, said brace forming with said wall a closed box section and having its top formed as a channel, the bottom of said channel sloping at least toward one of said posts, which post at the meeting point with said bottom is provided with an opening, said last-named post having another opening at its lower end so that the top of said brace and the last-named post constitute a drainage structure.

4. In an end wall for railway cars, a pair of hollow section collision posts flanking a passage opening in the wall, said posts having an opening at their lower ends and another opening near their upper ends in the wall facing the other post, a trough structure having a bottom sloping from a point between said posts, said brace interconnecting the posts and having the ends of said bottom at the level of the lower margin of the respective other opening so as to direct rain water collecting in the trough structure into the interior of the posts whence it is discharged through said first-named openings.

5. In an end wall for railway cars, a pair of hollow-section collision posts flanking a passage opening in the wall, each of said posts having a first opening at its lower end and a second opening near its upper end in the wall facing the other post, a trough structure having a bottom sloping from a point between said posts interconnecting the posts and having the ends of the bottom at the level of the lower margins of said other openings so as to direct rain water collecting in the trough structure into the interior of the posts whence it is discharged through said first-named openings, said trough structure forming with said wall, with a horizontal web and with a vertical web a triangular box sectional brace between said posts and serving for the support of a diaphragm suspension spring.

6. End wall for railway cars having a pair of transversely spaced vertical collision posts, lifting ears formed at the upper ends of said posts, said posts below the ears presenting box sections open at their lower ends, a cross member interconnecting said posts below said ears and forming a drain trough, openings in said posts at the level of the ends of the trough so as to let water collected by the trough run into the interior of the posts whence it is discharged through the lower open ends.

7. End wall for railway cars having a pair of

transversely spaced vertical collision posts, lifting ears formed at the upper ends of said posts, a cross member interconnecting said posts below said ears and forming a drain trough, openings in said posts at the level of the ends of the trough for the discharge of water collecting in the trough.

3. In a railway car, an end wall, a hollow-section elongated reinforcement secured to and extending vertically across said wall, a trough structure extending from and transversely to said reinforcement in the upper region but spaced from the upper margin of said end wall, an opening in one side of said reinforcement communicating with said trough structure, said reinforcement having another opening at its lower end so that it serves as drain pipe for water collected by said trough structure, further openings at the upper end of said reinforcement, an annular member in the interior of the upper end of the reinforcement having its opening in registry with said further openings and being structurally connected to the reinforcement so as to present an ear for lifting the car.

9. In a railway car, an end wall, a pair of hollow-section collision posts secured to the out-

side of said wall, a roof having its one end margin secured to the top margin of said wall, a pair of hollow-section purlines forming part of said roof and each one of them being lined up with and adjoining one of said posts, the walls of said posts, which extend in the longitudinal direction of the car, having openings in their ends adjoining the purlines, a reinforcing member in each of said posts surrounding said openings and projecting inwardly beyond the margins of the openings into said post and purline to which it is structurally connected to serve as ears for lifting the car, the weight of the car when lifted by the ears being transferred from the ears to the posts and purlines and thence distributed into the end wall and roof.
